DESIGN FOR A HAT

Martin Berg, New York, N. Y.

Application April 16, 1938, Serial No. 76,569

Term of patent 7 years

To all whom it may concern:

Be it known that I, Martin Berg, a citizen of Germany, residing at New York city, county and State of New York, have invented a new, original, and ornamental Design for a Hat, of which the following is a specification, reference being had to the accompanying drawing, forming a part thereof.

Fig. 3 is a front view of the hat shown in Fig. 2.

Fig. 4 is a side view thereof.

I claim:

The ornamental design for a hat, as shown.

MARTIN BERG.
